UNITED STATES PATENT OFFICE.

MOSES MOSLER, OF CINCINNATI, AND CARL BARTELS, OF HAMILTON, OHIO,
ASSIGNORS TO THE MOSLER SAFE COMPANY, OF NEW YORK, N. Y.

FIREPROOF SAFE.

1,118,435.

Specification of Letters Patent. Patented Nov. 24, 1914.

Application filed April 9, 1914. Serial No. 830,614.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Fireproof Safes, of which the following is a specification.

10. This invention, pertaining to fireproof safes, relates particularly to a construction by means of which the interior cabinet of the safe remains water-proof and steam-proof in spite of such warping distortion as may take place in the outer structure if a safe falls in a burning building and becomes highly heated and flooded with water, or otherwise flooded or subjected to the action of steam.
15. It frequently happens that a fire-proof safe falls to the lower regions in the burning building, the heat received by the safe causing such warping distortion as will open up joints to such extent as to permit of the admission of water or steam into the interior cabinet of the safe, to the damage or destruction of its contents, and damage is often done to the interior of ordinary safes in case of floods.
20. Our invention will be readily understood from the following description taken in connection with the accompanying drawings in which:—

Figure 1 is an elevation of the inner face of the general door embodying an exemplification of our improvements, a portion of the back-plate of the door being broken away to exhibit some of the bolt-work of the main door, and the bolt-work of the auxiliary door being omitted in order that the bolt-work of the main door may be more clearly seen. Fig. 2 is a similar elevation of the inner face of the auxiliary door, a portion of its inner plate being broken away: Fig. 3 a vertical section of the general door in the plane of line *a* of Figs. 1, 2 and 4: Fig. 4 a horizontal section at one edge of the general door in the plane of line *b* of Figs. 1, 2 and 3: Fig. 5 a vertical section at the upper edge of the main and auxiliary doors in the plane of line *a* of Figs. 1, 2 and 4: Fig. 6 a front elevation of one of the suspension elements uniting the auxiliary door to the main door; and Fig. 7

a horizontal section in the plane of line *c* of Figs. 1, 2 and 3.

In the drawings:—1, indicates the stepped door-jamb of a fire-proof safe: 2, the front plate of the front wall, surrounding the door-jamb: 3, the inner cabinet of the safe, having its front secured to the rear portion of the door-jamb: 4, the stepped frame of the main door, the same fitting within the stepped door-jamb: 5, the front plate of the main door: 6, the back-plate of the main door, this plate separating the main door into a front compartment to receive the bolt and lock work: 7, the fire-proof filling in the front compartment of the main door: 8, the main bolts, disposed in the rear compartment of the main door and working through its frame and adapted to lock into openings in the door-jamb: and 9, the carrying-bar for main bolts 8. All of the parts thus far referred to may be as usual in fire-proof safe construction and subject to any of the usual modifications in such construction, except as to a feature of the interior cabinet 3, which will be referred to later. Bolts 8 may be thrown by any of the usual means and our present invention does not concern itself with the mechanism for or manner of supporting the main door or operating its bolts.

Continuing with the drawings:—10, indicates an auxiliary door in the form of a plate carried by the main door frame but adapted for movement to and from the main door frame, this auxiliary door standing close to the front edge of the interior edge of the interior cabinet 3 when the compound door is closed; 11, a packing, as of rubber held by each face of the auxiliary door 10 and adapted to close tightly against the front edge of the cabinet 3 when the auxiliary door is moved inwardly away from the closed main door; 12, the frame of the auxiliary door, this frame being rigidly secured to the auxiliary door and being illustrated as having an angle cross-section, the outer margin of this frame fitting within one of the steps of the door-jamb; 13, auxiliary bolts carried by the auxiliary door and adapted to work through suitable openings in the auxiliary door-frame and engage in suitable openings in the door-jamb, these auxiliary door bolts being provided at all of the edges of the auxiliary door; 14,

the joint of separation between the front of auxiliary door-frame 12 and the rear of main door-frame 4, Fig. 4 indicating this joint as being open, while Figs. 3 and 5 illustrate it as being closed; 15, a vertical carrying bar connected with each vertical line of auxiliary bolts 13; 16, bearings through which the auxiliary bolts may slide in addition to other bearings in the auxiliary door-frame; 17, a spring surrounding each auxiliary bolt and compressed between the bearing 16 and a cross-pin in the bolt; 18, a pair of bell-crank levers mounted on fixed pivots on auxiliary door-plate 10 at the base of the auxiliary door, another pair being at the top, an arm of each of these bell-crank levers being connected with an end of an auxiliary carrying-bar so that the rocking of these bell-crank levers will move the carrying-bars laterally; 19, a pair of levers mounted on fixed pivots on the auxiliary door at the base of the door, another pair of these levers being provided at the top of the door, the outer end of each of these levers being pivoted to the inner arm of one of the bell-crank levers; 20, a crank-disk mounted within the auxiliary door, and preferably at the center of the door as illustrated; 21, a spindle fast with this crank-disk and adapted to be turned from the outer face of the main door as is usual in fireproof safes; 22, links extending from the crank-pins of the crank-disk to pivots uniting the inner ends of levers 19; 23, a typical tumbler of the usual combination lock mounted at the back of the main door, between it and the auxiliary door; 24, the usual dogging-bar attached to the carrying-bar 9 of the main bolts and extending inwardly past the combination lock, this dogging-bar having an inwardly presenting shoulder; 25, a locking-lever mounted on the main door on a pivot disposed below and between the combination lock and crank-disk 20, this locking-lever having a tooth adapted to enter the tumbler of the combination lock, and having an outer end adapted to engage inwardly of the shoulder on dogging-bar 24 when the main bolts are thrown and the tooth of the lever is out of the notch of the tumbler; 26, a pin carried by crank-disk 20 and adapted to engage over the inner end of locking-lever 25 when the tooth of the locking-lever is in the tumbler, and the auxiliary bolts are in drawn position, and adapted to engage inwardly of the inner end of the locking-lever when the auxiliary bolts are in thrown position and the tooth of the locking-lever is out of the notch of the tumbler; 27, a socket secured near each upper corner of main door-frame 4; 28, a block adapted to slide forward and backward in each of these sockets and having its rear end secured rigidly to auxiliary door-plate 10; 29, a spring acting

between each of the sockets and its block 28 and adapted to urge the auxiliary door toward the main door frame; and 30, a ball-bearing at each of the sockets, and acting between the socket and its block and serving to ease the forward and rearward motion of the blocks in the sockets. 70

The cabinet 3 is to be of metal with its seams made water-tight as by being welded. The auxiliary door may move to and from the main door a limited distance, blocks 28 sliding in sockets 26 as this motion takes place, and the springs 29 serving to urge the auxiliary door toward the main door so that joint 14 will be closed, the compound door then appearing as a single door. The socket and block arrangements at the top of the door form suspension elements uniting the auxiliary door to the main door. These arrangements might be duplicated at 80 the base of the door, but they are not necessary. 75

When the compound door is closed, and before the bolts of the auxiliary door are thrown, the packing on the auxiliary door stands free of the front edge of the cabinet 3, such relationship of parts permitting ordinary and frequent closing of the compound door during the day without subjecting the packing to any wear. The outer ends of auxiliary bolts 13 are beveled on their front faces where they engage the locking openings in the door-jamb, as seen in Fig. 4. If the compound door be closed in the usual manner, the auxiliary door will be without any special office, and joint 14 will be closed. If, now, the auxiliary bolts 13 be thrown then their beveled ends will cause the auxiliary door to be forced rearward so as to compress its packing tightly 100 against the front edge of the interior cabinet. Under these conditions the auxiliary door forms a water-tight closure for the interior cabinet and is not dependent upon the condition of the main door. The main door may become warped by fire and falling, or may fundamentally leak, but these damaging effects do not reach the auxiliary door, the result being that there is maintained within the fire-proof outer structure an inner water and steam-proof structure. It is to be observed that the connections between the auxiliary door and the main doors are of flexible character. 110

Springs 17 tend to urge the auxiliary bolts outward to locking position and to draw the auxiliary door to tightly packed position, the illustrated mechanism for operating these bolts being of a permissive and releasing character rather than elements essential in holding these bolts in active position. It is to be observed that the auxiliary bolts at the side edges of the door are moved by carrying-bars 15, while the auxiliary bolts at the upper and lower edges 115 120 125 130 135 140 145 150 155 of the door are actuated by oscillation of levers 19, the junctures of these levers with the inner arms of bell-crank levers 18 being engaged by these vertical bolts.

5 As seen in Figs. 1 and 2 the main bolts and the auxiliary bolts are in drawn position, and if it be desired merely to close the door of the safe without bolting it, the bolts may be left in this condition. The 10 main bolts may be thrown in the usual manner, whenever desired, the engagement of locking-lever 25 with dogging-bar 24 being an idle one. If, after the main bolts are thrown, it be desired to put the auxiliary door on duty it may be done by turning crank-disk 20, in clockwise direction in Fig. 2, which results in all of the auxiliary bolts going into action and drawing the auxiliary door into tight engagement with 15 the cabinet. This turning of the crank-disk has removed pin 26 from over the dogging lever so that the combination lock may be operated to cause the locking-lever to lock dogging-bar 24 and also to lock the crank-disk. When it is desired to unlock and open 20 the safe, the combination lock is first set and then the main bolts thrown, the action of dogging-bar 24 on the locking-lever releasing pin 26 so that the auxiliary bolts 25 may be drawn.

Our invention is quite independent of any peculiarity of means which may be employed in throwing the main bolts or in throwing and releasing the auxiliary bolts.

30 It is our preference that the springs throwing the auxiliary bolts have within themselves power enough to throw those bolts and draw the auxiliary door to tight condition independent of any other actuating mechanism that may be connected with those bolts. It might even be that under some circumstances of construction the springs which throw the auxiliary bolts will be strong enough to throw them and move 35 their connected mechanism when there was no desire that those bolts be thrown at all. We may therefore so connect the auxiliary bolts with the main bolts that the auxiliary bolts cannot throw unless the main bolts are thrown. This provision is of special utility 40 when the door is standing open, a condition under which it is undesirable that the auxiliary bolts be in thrown condition, for their protrusion would obviously interfere 45 with the ready closure of the door. And so, also, when the compound door is closed, but not locked, it is undesirable that the auxiliary bolts go to thrown position. This feature will now be explained.

50 Referring to the drawing, and particularly to Fig. 7:—31, indicates a short vertical spindle near that edge of the compound door provided with main bolts: 32, a slot in main carrying-bar 9: 33, an arm whose axis 55 is formed by spindle 31, this arm projecting

loosely into the slot in the main carrying-bar: and 34, an arm fast with arm 33 and adapted to swing rearward and have its inner end engage the edge of auxiliary carrying-bar 15.

70 In Fig. 7 the main bolts and auxiliary bolts are shown as thrown, corresponding with the locked condition of the compound door. If, by any mechanism whatever provided for the purpose, carrying-bar 15 be moved and the auxiliary bolts withdrawn, and then the main bolts be drawn, arm 34 will engage carrying-bar 15, thereby holding the auxiliary bolts in drawn condition regardless of the strength of their throwing 75 springs. In this condition of the compound door it may stand open, with all bolts drawn or it may be closed without any bolts being thrown. When the main bolts are thrown then the auxiliary bolts are released so that 80 they will be thrown by their springs or by whatever mechanism is provided for throwing them. The double lever 33—34 may be applied at any point in the height of the door where it can be acted upon by the main bolt system and serve in latching and releasing the auxiliary bolt system.

85 It is to be understood that the illustrated construction is but a single exemplification of our invention, which will lend itself to 90 many modifications at the hands of the skilled constructor without departing from the spirit of our invention. We have sought simply to set forth the principle of our invention and the best form in which we at 95 present contemplate embodying that principle.

100 We claim:—

1. A safe comprising, a main door, main bolt-work mounted thereon, a water-tight cabinet secured to the rear portion of the doorjamb, an auxiliary door carried by the rear of the main door and adapted to move to and from the main door, a packing between the auxiliary door and the front edge of the cabinet and adapted to be compressed when the main door is closed and the auxiliary door is moved away from it, means holding the auxiliary door normally toward the main door, and means independent of the main bolt-work and carried by the auxiliary door for forcing it away from the main door, combined substantially as set forth.

105 2. A safe comprising, a main door, main bolt-work mounted thereon, a water-tight cabinet secured to the rear portion of the doorjamb, an auxiliary door carried by the rear of the main door and adapted to move to and from the main door, a packing between the auxiliary door and the front edge of the cabinet and adapted to be compressed when the main door is closed and the auxiliary door is moved away from it, auxiliary bolt-work carried by the auxiliary door in- 110

dependent of the main bolt-work, and means carried by the auxiliary door for forcing it away from the main door when the auxiliary bolts are thrown, combined substantially as set forth.

3. A safe comprising, a main door, main bolt-work mounted thereon, a water-tight cabinet secured to the rear portion of the doorjamb, an auxiliary door suspended at the rear of the main door and adapted to move to and from the main door, a packing between the auxiliary door and the front edge of the cabinet and adapted to be compressed when the main door is closed and the auxiliary door is moved away from it, means holding the auxiliary door normally toward the main door, and means independent of the main bolt-work and carried by the auxiliary door for forcing it away from the main door, combined substantially as set forth.

4. A safe comprising, a main door, main bolt-work mounted thereon, a water-tight cabinet secured to the rear portion of the doorjamb, an auxiliary door carried by the rear of the main door and adapted to move to and from the main door, a packing between the auxiliary door and the front edge of the cabinet and adapted to be compressed when the main door is closed and the auxiliary door is moved away from it, and auxiliary bolts carried by the auxiliary door independent of the main bolt-work and having beveled ends adapted to force the auxiliary door away from the main door and toward the cabinet when the auxiliary bolts are thrown, combined substantially as set forth.

5. A safe comprising, a main door, main bolt-work mounted thereon, a water-tight cabinet secured to the rear portion of the doorjamb, an auxiliary door disposed at the rear of the main door, coöperating blocks and sockets on the main door and auxiliary door to cause the main door to support the auxiliary door and permit the latter to move to and from the former, a packing between the auxiliary door and the front edge of the cabinet and adapted to be compressed when the main door is closed and the auxiliary door is moved away from it, and means independent of the main bolt-work and carried by the auxiliary door for forcing it away from the main door, combined substantially as set forth.

6. A safe comprising, a main door, main bolt-work mounted thereon, a water-tight cabinet secured to the rear portion of the doorjamb, an auxiliary door disposed at the rear of the main door, coöperating blocks and sockets on the main door and auxiliary door to cause the main door to support the auxiliary door and permit the latter to move to and from the former, springs coöperating with the main door and auxiliary door and

tending to hold the auxiliary door yielding toward the main door, a packing between the auxiliary door and the front edge of the cabinet and adapted to be compressed when the main door is closed and the auxiliary door is moved away from it, and means independent of the main bolt-work and carried by the auxiliary door for forcing it away from the main door, combined substantially as set forth.

7. A safe comprising, a main door, main bolt-work mounted thereon, a water-tight cabinet secured to the rear portion of the doorjamb, an auxiliary door carried by the rear of the main door and adapted to move to and from the main door, a packing between the auxiliary door and the front edge of the cabinet and adapted to be compressed when the main door is closed and the auxiliary door is moved away from it, auxiliary bolt-work carried by the auxiliary door independent of the main bolt-work, means carried by the auxiliary door for forcing it away from the main door when the auxiliary bolts are thrown, and springs co-acting with the auxiliary bolt-work to serve in throwing and holding thrown the auxiliary bolts, combined substantially as set forth.

8. A safe comprising, a main door, main bolt-work mounted thereon, a water-tight cabinet secured to the rear portion of the door-jamb, an auxiliary door carried by the rear of the main door and adapted to move to and from the main door, a packing between the auxiliary door and the front edge of the cabinet and adapted to be compressed when the main door is closed and the auxiliary door is moved away from it, auxiliary bolts carried by the auxiliary door, and spring mechanism for throwing the auxiliary bolts and drawing the auxiliary door away from the main door and tightly toward said cabinet, combined substantially as set forth.

9. A safe comprising, a main door, main bolt-work mounted thereon, a water-tight cabinet secured to the rear portion of the door-jamb, an auxiliary door carried by the rear of the main door and adapted to move to and from the main door, a packing between the auxiliary door and the front edge of the cabinet and adapted to be compressed when the main door is closed and the auxiliary door is moved away from it, auxiliary bolts carried by the auxiliary door and serving to move the auxiliary door away from the main door and tightly against the cabinet, and a latching device coöperating with the main bolts and serving to prevent the auxiliary bolts from being thrown before the main bolts are thrown, combined substantially as set forth.

10. A safe comprising, a main door, main bolt-work mounted thereon, a water-tight cabinet secured to the rear portion of the

doorjamb, an auxiliary door carried by the rear of the main door and adapted to move to and from the main door, a packing between the auxiliary door and the front edge 5 of the cabinet and adapted to be compressed when the main door is closed and the auxiliary door is moved away from it, auxiliary bolt-work carried by the auxiliary door independent of the bolt-work, means carried 10 by the auxiliary door for forcing it away from the main door when the auxiliary bolts are thrown, and means for locking the main bolt-work and auxiliary bolt-work when both sets of bolts are in thrown position, 15 combined substantially as set forth.

11. A safe comprising, a main door, main bolt-work mounted thereon, a water-tight cabinet secured to the rear portion of the doorjamb, an auxiliary door carried by the 20 rear of the main door and adapted to move to and from the main door, a packing be-

tween the auxiliary door and the front edge of the cabinet and adapted to be compressed when the main door is closed and the auxiliary door is moved away from it, auxiliary bolt-work carried by the auxiliary door independent of the bolt-work, means carried by the auxiliary door for forcing it away from the main door when the auxiliary bolts are thrown, a dogging-bar moving with the 25 main bolts, a dogging-member moving with the auxiliary bolts, a lock, and a locking lever controlled by the lock and coöperating with said dogging-bar and dogging-member and serving to hold both sets of bolts in 30 thrown position, combined substantially as 35 set forth.

MOSES MOSLER.
